On closed circuit the impulses may be generated by opening the circuit, by connecting or disconnecting resistances or by weakening or strengthening THE NORRIS PET the current.

UNITED STATES PATENT OFFICE.

ADOLF FRANKE, OF HALENSEE, NEAR BERLIN, GERMANY, ASSIGNOR TO SIEMENS & HALSKE, A. G., OF BERLIN, GERMANY, A CORPORATION OF GERMANY.

SYSTEM FOR SELECTING ONE OF SEVERAL RECEIVERS CONNECTED TO A COMMON CONDUCTOR.

No. 888,153.

Specification of Letters Patent.

Patented May 19, 1908.

Application filed December 23, 1907. Serial No. 407,788.

To all whom it may concern:

Be it known that I, ADOLF FRANKE, a subject of the German Emperor, and residing at Westfälischestrasse 59, Halensee, near Berlin, Germany, have invented certain new and useful Improvements in Systems for Selecting One of Several Receivers Connected to a Common Conductor, of which the following is a specification.

10 The present invention relates to an electric system for selecting one of several receivers connected to one common conductor. In accordance with the invention this selection is brought about by each of the 15 magnets which are used for selecting and which adjoin the individual receivers, switching into circuit a switching mechanism by means of a long continued variation of the electrical state which is produced in the conductor; the switch mechanism adjoining a receiver is then switched forward by a number of short variations of current produced in the conductor in optional sequence as to time and corresponding in number to the receiver 20 which is to be selected, and by a subsequent long continued variation of current. In this position of the selecting switch the long continued variation of current also causes a signal or the like to be given at the selected station.

30 The installation can be worked with transmission or with closed-circuit current. In the former case the common conductor leading to the receivers is without current in its normal state, and impulses of current of shorter or longer duration are sent into the conductor when selecting. When the installation works with closed-circuit current, the common conductor of the receivers has a current flowing through the same in its normal state, whereas, when selecting, the short or long continued variations of the electrical state can be brought about either by interrupting the current, by connecting or disconnecting resistance, or by weakening or strengthening the current. Further, the installation can be so arranged that the switch-mechanism adjoining each receiver is switched by the variations of current produced in the line containing the receivers, *i. e.* the distant line, or the variations of current can influ-

ence a local circuit at each receiver by means of a relay, which local circuit operates the switch-mechanism.

In order that the invention may be clearly understood reference is made to the accompanying drawing in which two embodiments of the electrical selector system are represented diagrammatically.

In the drawing:—Figure 1 shows the invention used in connection with a system worked with transmission current, whereas Fig. 2 shows a system operated with closed-circuit current to which the invention is applied.

65 In the installation according to Fig. 1 the electromagnets e_1, e_2, e_3, e_4 , which each adjoin a receiver and are connected with a switching device are situated in a circuit with the battery b and key a , the latter being open in its 70 normal position. The switching device H_4 adjoining the receiver-electromagnet e_4 only is represented in the drawing. In its normal position the armature c of the electromagnet e_4 keeps the contact c_1 open and is influenced 75 by the retarding device f . The switch-disk h is on one and the same axle with the ratchet wheel h_1 , the latter being rotated by the armature of the switching electromagnet i . If the operator at the key a wishes to select, 80 for example, the receiver e_4 of which he knows that for this selection five variations of current in the receiver-line are used, by depressing key a he first causes a long continued flow 85 of current in the receiver-line l_1 , whereby, besides others, the electromagnet e_4 is energized. The armature c is slowly attracted until the contact c_1 is closed, the resistance which is offered by the retarding device f being overcome. A current then flows from 90 the battery b through key a , receiver-line l_1 , armature c , contact c_1 , brush g_2 , selecting contact-ring k_2 , brush g_3 , conductor l_2 , switching electromagnet i , conductor l_2 and through conductor l_{10} back to the battery b . The armature i_1 is therefore attracted, rotates the ratchet-wheel h_1 and with it the contact disk or drum h one tooth forward, and brings the brush g_3 onto the circuit contact-ring k_3 . The switching device H_4 is thereby connected directly to the line l_1 , *i. e.* bridging over the contact c_1 of the retarding

device because contact-ring k_3 is connected electrically with contact-ring k_1 . When the key a is now released, the electromagnet i becomes without current, the armature i_1 moves away and moves the pawl on it behind the next tooth of the ratchet-wheel h_1 . Now as the receiver e_4 which is to be selected can be brought into the selecting position, *i. e.* the position in which it can be called, by 10 five variations of current, not counting the above mentioned initial long continued flow of current, the key a is first depressed for a short time four times successively and then a long continued variation of current is 15 caused the fifth time. Each impulse or rush of current proceeding from the battery b and flowing back through the key a , receiver-line l_1 , conductor l_3 , brush g_1 , contact-ring k_1 , contact-ring k_3 , brush g_3 , conductor l_4 , ratchet-magnet i , conductor l_2 , conductor l_{10} to the battery b switches the switching device one step forward, and the fifth rush of current brings the same into the selecting position in which the ring k_2 is electrically connected with the 20 brush g_4 . Under the influence of the fifth long continued closure of the circuit the contact c of the retarding device is again closed, the consequence of which is that a current flows through armature c , contact c_1 , brush 25 g_2 , contact-ring k_2 , brush g_4 , and the call-bell or alarm w or the like. The alarm w sounds and announces to the concerned operator that he or his receiver is wanted.

The number of the rushes or impulses of 30 current which is necessary for moving the switching device into the selecting position is dependent as is easily seen on the position of the brush g_4 relatively to the disk or drum h ; this position is different in the mentioned 35 selecting switches, so that for bringing about the selecting position of the individual selecting drums, a varying number of rushes of current must be sent through the conductor. The first long continued rush of 40 current which is not counted has no other duty to perform than to release all the selecting switches connected to the conductor, *i. e.* to make them operative for the short impulses of current which are then sent.

45 The mode of carrying out the invention which has been described with reference to the drawing is particularly suitable for telegraph installations with Morse operation, in which several Morse apparatus are connected 50 in series in one loop line and can be called from one common sender station. In order to be able to select from these as desired one definite Morse apparatus, a selecting switch is arranged at each of them. The selection 55 is then effected in the above described manner. The sounding of the call-bell at the selecting switch causes the concerned operator to set his Morse apparatus for the receipt of the telegram. The Morse signals

which are then sent through the line by 65 means of the key a are recorded by the Morse apparatus which is connected in circuit, and at the same time switch the selecting switch into the normal position. It is self evident that for closing the contact of the retarding 70 device at the selecting switch, a substantially longer impulse of current must be chosen than those necessary for recording the Morse dash, as otherwise the latter could cause the release of a selecting switch. This can be 75 very easily attained by employing a suitable retarding device.

The switching device could be returned into its normal position in another manner also, as, for example, by each of the switch-disks or drums stretching a spiral spring mounted round its axle when it is moved forward. The spiral springs of all the switching mechanisms could be released electromagnetically after the selection is finished, 85 and the switching devices of all the receivers could be thereby returned automatically into their commencing position.

The arrangement represented diagrammatically in Fig. 2 operates with closed-circuit current in contradistinction to the arrangement according to Fig. 1. Here again an electromagnet, ratchet mechanism and switching device are arranged adjoining each receiver. The manner in which the installation is worked is the same as that described with regard to Fig. 1. Not one of the switching devices, for example H_4 , is influenced directly by the variations of current produced in the distant line l_1 however, but 90 by means of a local battery b_1 . If, for example, the receiver e_4 is to be selected, of which the operator working the switch a knows that it can be selected and that the switching device can be cut out by one long continued interruption of current and by means of four short and one subsequent long continued interruption of current in the distant line l_1 , the closed-circuit distant line l_1 is first opened by depressing the key a until the retarding 95 device f at the receiver has closed the contact c_1 of the retarding device. A circuit is thereby made as follows:—local battery b_1 , conductor l_7 , armature c , contact c_1 , conductor l_8 , selecting-contact strip k_1 , brush g_1 , 100 conductor l_4 , electromagnet i , conductor l_2 , local battery b .

The ratchet-electromagnet i therefore attracts its armature i_1 , rotates the ratchet-wheel h_1 and with it the drum h in the direction of the arrow, so that the brush g_1 passes onto the circuit contact-ring k_2 . The switch can now be moved further into the selecting position by four short interruptions of current in the line l_1 and one subsequent long 110 continued interruption. In the case of these first interruptions only the contact c_2 , c_3 will be closed by making the receiver e_4 without 115

current, whereas when the subsequent long continued interruption of current takes place, on account of which the contact-brush g_4 comes onto the contact-strip k_1 , the retarding contact c_1 is closed and a signal is given by the call-bell or alarm w . The current flows from the battery b_1 through conductor l_7 , armature c , contact c_1 , conductor l_8 , contact-strip k_1 , brush g_4 , alarm w and 10 through conductor l_5 back to the battery b_1 .

In the selecting operation the switching device adjoining the remaining receivers have also been switched forward, but they have not come into their position for giving a 15 call-signal, as the position of the brush g_4 with regard to the switch-drum h is a different one in the case of all the receivers. This arrangement also is suitable for telegraph installations with Morse operation, and what 20 has been said above in this respect with regard to Fig. 1 holds good here.

If the switching device of the receiver which is to be selected has arrived into the position in which it gives the signal, a circuit 25 can be closed at the same time by a relay, and after the key a is closed again in the line l_1 after the last long continued variations of the electric state, this closed relay circuit will set the signal in operation until the 30 called subscriber or operator steps up to the apparatus, stops the alarm or the like and, in a given case, sets the writing apparatus for the reception of a telegram.

The electrical selecting system can of 35 course be employed everywhere where it is a question of setting into or out of operation one optional battery, motor, apparatus or the like which is to be selected from a number of batteries, motors, apparatus or the like. The form of construction can be varied corresponding to the purpose of employment in each case. It is only essential in each case that the selection is made by means of receivers in a closed circuit by first a long 40 continued variation of current and then a number of short variations corresponding to the receiver which is to be selected, a subsequent long continued change of the electrical state being produced in this circuit.

50 What I claim as my invention and desire to secure by Letters Patent is:—

1. In an electrical selecting system of the type described, a plurality of receiver-electromagnets, a source of current, a switch and 55 a line connecting the same in series, in combination with a second switch adapted to be operated by one of said receiver-electromagnets, a retarding device controlling said second switch, a switching device, means for 60 operating the latter controlled by said second switch, and an alarm device connected with and controlled by said switching device, the arrangement being such that the switching device can be switched into the se-

lecting position in which a signal can be sent 65 to the station which is selected under the influence of a number of short variations of current produced in the line and corresponding to the receiver which is to be selected, and under the influence of a succeeding long 70 continued variation of the electric state in the line.

2. In an electrical selecting system of the type described, a plurality of receiver-electromagnets, a source of current, a switch and 75 a line connecting the same in series, in combination with a switching device adjoining one of said receiver-electromagnets and carrying a plurality of contacts, an electromagnet adapted to drive said switching device; a 80 second switch, a retarding device controlling the latter, an alarm and conductors connecting said second switch, switching device and alarm in a circuit in series with one another and in parallel with one of said receiver-electromagnets; and conductors connecting said 85 switching device and said electromagnet adapted to drive the same in a circuit in series with one another and in parallel with the latter circuit, the arrangement being such 90 that when a long continued rush of current is sent through the line, the second switch is closed and thereby the current from the line flows through the switching device, and the latter can be switched into the selecting position under the influence of short impulses of 95 current sent through the line and under the influence of one subsequent long continued rush of current in the line.

3. In an electrical selecting system of the type described, a plurality of receiver-electromagnets, a source of current, a switch and 100 a line connecting the same in series, in combination with a second switch adjoining a receiver-electromagnet and a retarding device controlling the latter switch; a switching device carrying a circuit-contact and a selecting-contact, ratchet mechanism adapted to operate the switching device and an electromagnet for operating said ratchet mechanism; an alarm; conductors connecting said circuit-contact and said second switch with one side of the latter receiver-electromagnet, conductors connecting the other side of the latter with said alarm and with said ratchet- 110 mechanism; controlling electromagnet, a conductor normally connecting the latter with said selecting-contact and a conductor for connecting the alarm with the latter contact when the switching device is driven into the selecting 115 position for the receiver-electromagnet which it adjoins, and a conductor connecting said selecting-contact with the contact of the second switch, the arrangement being such that when the switching device is operated by a 120 long continued variation of current in the line, the second switch is bridged over so that short impulses of current sent through

125

the line can energize the ratchet-electromagnet and finally the alarm when the same is connected with the selecting-contact, so that in this position of the switching device a long continued rush of current through the line causes a signal to be given at the concerned receiving-station.

In testimony whereof I have signed my name to this specification in the presence of two witnesses.

ADOLF FRANKE.
